(57) **CLAIM**

The ornamental design for a hammock chair, as shown and described.

DESCRIPTION

FIG. 1 is an isometric view of a first embodiment of a hammock chair showing our new design during use; FIG. 2 is an isometric view thereof, but shown flattened; FIG. 3 is a top view thereof; FIG. 4 is a bottom view thereof; FIG. 5 is a front view thereof; FIG. 6 is a back view thereof; FIG. 7 is a left side view thereof; FIG. 8 is a right side view thereof; FIG. 9 is an isometric view of a second embodiment of a hammock chair showing our new design during use; FIG. 10 is an isometric view thereof, but shown but shown flattened; FIG. 11 is a top view thereof; FIG. 12 is a bottom view thereof; FIG. 13 is a front view thereof; FIG. 14 is a back view thereof; FIG. 15 is a left side view thereof; and, FIG. 16 is a right side view thereof.

Those portions of the figures that are presented in broken lines merely illustrate the environment of the design and are not part of the claimed design.
